(57) **CLAIM**

The ornamental design for a machine handle, as shown and described.

DESCRIPTION

1. Machine handle

1.1 : Top

1.2 : Bottom

1.3 : Right

1.4 : Left

1.5 : Front

1.6 : Rear view

1.7 : Perspective

Machine handle composed of a central gripping element consisting of a thin band with a convex arched profile on the sides of which are present two basic elements composed of a central parallelepiped body, on whose sides are placed two semi-cylinders having a different base radius with respect to each other.
